UNITED STATES PATENT OFFICE.

LORENTZ O. REITAN, OF HAUGESUND, NORWAY,

FAN FOR BEDS.

1,376,289.

Specification of Letters Patent. Patented Apr. 26, 1921.

Application filed March 5, 1920. Serial No. 363,460.

To all whom it may concern:

Be it known that I, LORENTZ O. REITAN, a citizen of France, residing at Haugesund, Norway, have invented certain new and useful Improvements in Fans for Beds; and I do hereby declare the following to be a full, clear, and exact description of the invention, such as will enable others skilled in the art to which it appertains to make and use the same.

This invention relates to new and useful improvements in fans for beds and has for one of its objects the provision of a device of this character which can be easily installed on a bed for the purpose of fanning and keeping cool the occupants of the bed, thus rendering the device especially adaptable for use in tropical countries wherein it is difficult to sleep on account of the excessive heat.

Another object of this invention is the provision of a fan for beds of the above stated character, which shall be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawings, in which:—

Figure 1 is a side elevation partly in section of a bed illustrating a fan applied thereto and constructed in accordance with my invention,

Fig. 2 is an enlarged side elevation of the device removed from the bed,

Fig. 3 is a sectional view taken through the fan, and support.

Referring in detail to the drawings, the numeral 1 indicates a bed having mounted thereon an ordinary mosquito bar supporting frame 2 to which my invention is applicable.

A supporting bar 3 is secured to the frame 2 in any desired manner and is provided with spaced bearings 4 which are adjustable and detachable from the bar. The bearings

4 have formed thereon hooks 5 to rotatably support an operating shaft 6 which extends parallel with the supporting bar and is provided with a crank 7 at one end to which a spring motor 9 is attached for oscillating the shaft 6. However, the spring motor may be substituted by an electrical motor, that is, when the device is used in places where it is possible to obtain electricity. The spring motor 9 is supported by the supporting rod 3 as illustrated at 10. Arms 11 are formed upon the operating shaft 6 to which is secured a frame 12. The frame 12 is covered by fabric 13 which projects beyond said frame and is slotted to form a plurality of strips 14 adapted to create a current of air during the oscillation of the frame 12. The frame 12 and strips 14 are disposed in close proximity to an occupant of the bed so that on setting the spring motor in operation, the frame 12 will be oscillated causing a current of air to be created against the occupant thereby keeping said occupant cool while sleeping in excessive heat.

While I have shown and described the preferred embodiment of my invention, it will be understood that minor changes in construction, combination, and arrangement of parts may be made without departing from the spirit and scope of the invention as claimed.

Having thus described my invention what I claim is:

A fan for beds comprising a supporting frame associated with a bed, a supporting rod carried by the frame and extending transversely of the bed, hangers adjustably secured to the rod, an operating shaft journaled in the hangers and extending parallel and in a plane below the rod, means for oscillating the shaft, arms formed on said shaft, a frame carried by said arms and disposed over the bed, and fabric secured to the frame and extending beyond the same at one end and having its free edge cut into a plurality of strips adapted to create a current of air by the oscillation of said frame.

In testimony whereof I affix my signature in presence of two witnesses.

L. O. REITAN.
